(57) **CLAIM**

The ornamental design for a bent tube quick hitch, as shown and described.

DESCRIPTION

FIG. 1 is a top left front perspective view of a bent tube quick hitch embodying our new design;

FIG. 2 is a bottom left rear perspective view of the bent tube quick hitch of FIG. 1;

FIG. 3 is a front elevational view of the bent tube quick hitch of FIGS. 1-2;

FIG. 4 is a rear elevational view of the bent tube quick hitch of FIGS. 1-3;

FIG. 5 is a top plan view of the bent tube quick hitch of FIGS. 1-4;

FIG. 6 is a bottom plan view of the bent tube quick hitch of FIGS. 1-5;

FIG. 7 is a right side elevational view of the bent tube quick hitch of FIGS. 1-6;

FIG. 8 is a left side elevational view of the bent tube quick hitch of FIGS. 1-7;

FIG. 9 is a top left front perspective view of a bent tube quick hitch embodying our new design;

FIG. 10 is a bottom left rear perspective view of the bent tube quick hitch of FIG. 9;

FIG. 11 is a front elevational view of the bent tube quick hitch of FIGS. 9-10;

FIG. 12 is a rear elevational view of the bent tube quick hitch of FIGS. 9-11;

FIG. 13 is a top plan view of the bent tube quick hitch of FIGS. 9-12;

FIG. 14 is a bottom plan view of the bent tube quick hitch of FIGS. 9-13;

FIG. 15 is a right side elevational view of the bent tube quick hitch of FIGS. 9-14; and,

FIG. 16 is a left side elevational view of the bent tube quick hitch of FIGS. 9-15.

The broken lines shown in the drawings illustrate portions of the bent tube quick hitch that form no part of the claimed design.
